Attorney

UNITED STATES PATENT OFFICE.

ARTHUR G. PALMER, OF DOVER PLAINS, NEW YORK.

PAPER NOVELTY ARTICLE.

Application filed December 21, 1926. Serial No. 156,166.

This invention relates to improvements in paper novelty articles of manufacture, having for an object to provide a novel form of paper party favor especially pleasing to children, wherein the usual crepe or similar paper covering is arranged about a tubular favor container, while a children's story booklet is arranged over a portion of the same and is secured in position upon the paper adjacent the tubular container by a transparent covering and retaining sheet, portions of which are joined by an adhesive to adjacent portions of the crepe paper, thus allowing the picture upon the exposed cover side of the booklet to be displayed through the sheet and at the same time, positively prevent the booklet from becoming displaced by either transverse or longitudinal movement.

It is also an object of the invention to provide a favor of the character described wherein the novelties arranged within the tubular container are held against longitudinal displacement therefrom by crimping portions of the crepe paper covering and the transparent covering sheet over the open opposite ends of said container, thereby constricting these openings and consequently, preventing longitudinal displacement of the novelties and similar devices from the container, yet allowing of free and uninterrupted passage of the extremities of the usual snapper therefrom in order that these extremities may be grasped in the hands of a guest and pulled apart whereby to effect a slight explosion; the slightly greater stiffness of the transparent covering sheet serving as an additional means for retaining the constricted or crimped portions of the crepe paper over the open opposite ends of the tubular container.

Other objects of the invention will be in part obvious and in part pointed out hereinafter.

In order that the invention and its mode of operation may be readily understood by those skilled in the art, I have in the accompanying illustrative drawings and in the detailed following description based thereupon, set out one possible embodiment of the invention.

In these drawings:

Figure 1 is a perspective view of my improved paper party favor illustrating the manner in which the picture carrying cover

page of a story booklet is displayed through the transparent covering sheet,

Figure 2 is a disassembled perspective view of the device, and

Figure 3 is an enlarged fragmentary detail, partly in longitudinal section, illustrating the manner in which the crepe paper and the adjacent extremities of the transparent covering and retaining sheet are crimped over the open opposite ends of the tubular container whereby to constrict their relative sides and also, illustrating the manner in which the picture story booklet is arranged over the peripheral surface of the tubular container adjacent the crepe covering paper and then, secured against displacement through the transparent covering and retaining sheet, portions of which are joined by an adhesive to adjacent portions of the crepe covering paper.

Having more particular reference to the drawings, in connection with which like characters of reference will designate corresponding parts throughout, the improved favor may be stated to comprise the usual hollow cylindrical or tubular novelty container 1, the opposite ends of which are open and adapted to receive therethrough, certain novelties, mottoes, printed upon slips of paper, etc., whereupon a heavy paper or similar material 2 is wrapped thereabout and has the opposite ends of the same extended for a distance beyond the opposite ends of the container 1, following which a finishing crepe covering paper 3 is then wrapped snugly about the container 1 and the paper 2, whereupon the longitudinal sides of said crepe covering paper are secured by a suitable adhesive to the paper 2, whereby to retain the same snugly about it together with the tubular container 1.

With the arrangement and securing of the crepe finishing covering paper 3 about the favor in the manner just described, a booklet, having fiction printed therein, together with certain illustrations is arranged over the peripheral surface of the container 1 adjacent a portion of the crepe covering paper 3, in the manner as is indicated in the Figure 1, whereupon a transparent covering and retaining sheet 4 is wrapped about the tubular container 1 over the adjacent portion of the crepe covering paper 2 and the exposed picture carrying cover 5 of the booklet 5', thereby snugly engaging said booklet about

the adjacent portion of the peripheral surface of the container 1, as is shown in the Figure 1, following which the longitudinal side portions of the covering and retaining sheet 4 are joined by a suitable adhesive to adjacent portions of the previously secured finishing and covering crepe paper 3. Preferably, the length of the booklet 5' is such as to approximately correspond to the length of 10 the tubular or hollow cylindrical container 1, thus bringing the opposite extremities of said booklet to positions approximately adjacent the opposite extremities of the tubular container 1, as is well illustrated in the 15 Figure 3, so that with subsequent treatment of the transparent covering and retaining sheet 4, said booklet will be provided with a means for positively preventing longitudinal shifting movement of the same with respect 20 to the container 1, in the manner hereinafter more fully described.

With snug arrangement of the transparent covering and retaining sheet 4 over the picture carrying story booklet 5', it will be appreciated that the picture 5 upon the exposed cover side of the booklet will be clearly displayed through said transparent sheet and by consequence, will serve to provide a novelty especially pleasing to children and 30 further, a novelty possessing material commercial merit in that because of the exposure of the picture carrying cover of the story booklet 5', the device or rather the novelty is rendered self selling, inasmuch as it needs 35 no explanation as to the contents of the booklet 5' due to the fact that said booklet, together with the name printed or otherwise presented thereupon and the picture carrying cover will be clearly visible to a prospective purchaser.

With a view toward providing the novelty with additional means for preventing displacement of the booklet 5' with respect to the tubular container 1, as by longitudinal 45 shifting movement, the extremities of the covering paper 2 together with the covering and finishing crepe paper 3 and the extremities of the transparent covering and retaining sheet 4 are crimped inwardly and at 50 abrupt angles with respect to the open opposite extremities of the tubular container 1, as is shown in the Figure 3, thereby partially closing said open opposite extremities of the container 1 and by such constriction 55 thereof, affording a means which will not only serve to definitely and positively locate the various sheets with respect to each other, but also, to prevent longitudinal displacement of the novelties or other devices contained within the container 1. At the same time, it will be understood that by such partial closure of the open opposite ends of the tubular container 1, the extremities 60 of the usual snapping device 6 arranged or 65 passed longitudinally through the container

1 will not be interfered with in any manner whatsoever, thus permitting of their arrangement without and beyond the opposite ends of the tubular container 1 in order that the snapping device may be broken and thus exploded during opening of the favor. 70

Furthermore, it is to be noted in this connection that because of the arrangement of the opposite extremities of the booklet 5 at 75 points approximately adjacent to the opposite extremities of adjacent portions of the tubular container 1, the crimped portion of the extremities of the transparent covering and retaining sheet 4 will be inturned abruptly or sharply over said opposite extremities of the booklet 5' as is indicated by the numeral 7, thereby creating adjacent these opposite extremities of the booklet, an efficient abutment means which will serve to 80 positively prevent any material longitudinal shifting movement of the booklet 5' with respect to the container 1.

To retain the transparent covering and retaining sheet 4 in its snugly wrapped position about the tubular container 1 and the 85 finishing crepe paper 3, the longitudinal side portions of said sheet 4 are joined by a suitable adhesive 8 to adjacent parts of the covering paper 3, as is shown in the Figure 3 and additionally, if desired, the opposite 90 extremities or ends of the covering sheet may be formed with a series of slits 9 so that with adhesive securing of said covering sheet together with the crimping of the extended 95 opposite portions of the same over the open 100 opposite ends of the container 1, said slit portions may be spread so as to provide the covering sheet with a fanciful and ornamental fringe, designated for convenience herein by the numeral 10, this fringe corresponding to the usual finishing fringe or 105 similar ornamentation formed upon the opposite extremities of the crepe covering and finishing paper as at 11.

Manifestly, the construction shown is 110 capable of considerable modification and such modification as is within the scope of my claims, I consider within the spirit of my invention.

I claim:

1. In combination with a party favor including a tubular container and a covering and finishing paper wrapped thereabout having the opposite ends extended beyond the ends of the container, a booklet 115 embrac- 120 ingly engaged over a portion of the paper adjacent the container, and a transparent covering and retaining sheet wrapped completely about and over said booklet and said covering and finishing paper, the opposite 125 longitudinal sides of said transparent sheet being joined by an adhesive to adjacent portions of the covering and finishing paper.

2. In combination with a party favor including a tubular container and a covering 130

and finishing paper wrapped thereabout having the opposite ends of the same extended beyond the ends of the container, a booklet embracingly engaged over a portion 5 of the paper adjacent the container, and a transparent covering and retaining sheet wrapped over and about the booklet and a portion of the covering and finishing paper, the extremities of said transparent covering 10 and retaining sheet being extended for distances beyond the opposite end of the tubular container, and said extremities of the transparent sheet and the covering and finishing paper being crimped inwardly with respect 15 to the open opposite extremities of the container.

3. In combination with a party favor, including a tubular container and a covering and finishing paper wrapped thereabout, a 20 booklet embracingly engaged over a portion of the paper adjacent the container, and a transparent covering and retaining sheet wrapped about and over said booklet and said covering and finishing paper and joined 25 to portions of the latter, the opposite extremities of said transparent sheet being crimped inwardly and abruptly over the opposite extremities of the booklet and par-

tially closing open opposite extremities of said container.

4. In combination with a party favor including a tubular container and a covering and finishing paper wrapped thereabout having its opposite ends extended beyond the ends of the container, a booklet embracingly engaged over a portion of the paper adjacent the container, and a transparent covering and retaining sheet wrapped about and over the booklet and the finishing and covering papers, the opposite extremities of 40 said booklet being arranged in proximity to the opposite extremities of the container, and the extremities of the transparent sheet extending beyond the opposite ends of said booklet and container and being crimped 45 inwardly over said opposite ends of the booklet and the container together with the covering and finishing paper whereby to secure said booklet against longitudinal shifting movement upon the container and 50 to partially close the open opposite extremities of said container.

In witness whereof I have hereunto set my hand.

ARTHUR G. PALMER.
